UNITED STATES PATENT OFFICE.

HARRY V. PADFIELD AND JOHN W. CORNELIUS, OF ST. LOUIS, MISSOURI.

DESIGN FOR A NUT-LOCK WASHER.

SPECIFICATION forming part of Design No. 30,440, dated March 28, 1899.

Application filed February 16, 1899. Serial No. 706,731. Term of patent 14 years.

To all whom it may concern:

Be it known that we, HARRY V. PADFIELD and JOHN W. CORNELIUS, citizens of the United States, residing in the city of St. Louis, 5 State of Missouri, have invented and produced a new and original Design for a Nut-Lock Washer, of which the following is a specification.

Figure 1 is a plan view of a nut-lock washer embodying our new design, and Fig. 2 is an edge view looking in the direction indicated by the arrow 2 in Fig. 1.

As shown in the drawings, the leading or essential feature of our design for a nut-lock

washer consists of the plate 3, having the central opening 4 and the tongue 5 at one side of and integral with the plate 3. The plate 3 has its ends curved downwardly, as shown in Fig. 2, and the free end of the tongue 5 is curved upwardly. 15

We claim—

The design for a nut-lock washer, substantially as herein shown and described.

HARRY V. PADFIELD.
JOHN W. CORNELIUS.
